CLAIM

The ornamental design for a golf club head, as shown and described.

DESCRIPTION

FIG. 1 is a front, top perspective view of the golf club head;

FIG. 2 is a bottom, rear perspective view thereof;

FIG. 3 is a top plan view thereof;

FIG. 4 is a bottom plan view thereof;

FIG. 5 is a toe-side elevational view thereof;

FIG. 6 is a heel-side elevational view thereof; and,

FIG. 7 is a bottom, rear, heel-side perspective view thereof.

The broken lines depict unclaimed portions of the golf club head, and thus form no part of the claimed design.
